UNITED STATES PATENT OFFICE.

JOHN T. JENNINGS AND THOMAS H. C. HOMERSHAM, OF BRADFORD,
ENGLAND.

DIRECT-ACTING PUMP.

SPECIFICATION forming part of Letters Patent No. 779,044, dated January 3, 1905.

Application filed July 20, 1903. Serial No. 166,834.

To all whom it may concern:

Be it known that we, JOHN THOMAS JENNINGS and THOMAS HENRY COLLETT HOMERSHAM, subjects of the King of Great Britain and Ireland, whose postal address is Vulcan Iron Works, Bradford, in the county of York, England, have invented certain new and useful Improvements in and Relating to Direct-Acting Pumps, of which the following is a specification.

This invention relates to improvements in direct-acting pumps, used principally for exhausting the water and vapor of condensation from steam-engines, but suitable for pumping any fluid, and in which the motive power is derived from steam or other fluid pressure, and has for its object the construction of the pump-barrel in such a manner that a simple and positive action is obtained.

In describing our invention in detail reference is made to the accompanying sheets of drawings, similar letters indicating similar parts, in which—

Figure 1 is a sectional elevation of a pump-barrel. Fig. 2 is a sectional elevation of the pump-barrel and one of the valves, showing a modification. Fig. 3 is a plan view of the barrel and valves. Fig. 4 is a sectional view through the valves.

In carrying out our invention in the pump-barrel A of a direct-acting pump are formed grooves B, Fig. 1, or ports C, Fig. 2, such grooves B or ports C reaching to the counterbore of the pump-barrel A, arranged in such a manner that when the plunger D is nearing the end of its stroke in either direction the grooves B or ports C form a connection between the spaces adjacent to the face of the plunger D and allow some of the fluid which is being pressed upon by the said plunger to escape to the opposite side of such plunger. Ports E and F act as both inlet and outlet ports, and each port is connected to a valve-chamber having therein ordinary check-valves 45 4 5, one opening inward for inlet and the other to outward for outlet, such valves being connected, respectively, to inlet and outlet

pipes—that is to say, there are two valve-chambers 1 2, separated by a plate 3 or other suitable means absolutely of ordinary description. One of these valve-chambers, 1, communicates with the top port E and the other, 2, with port F. As this part of the device is well known and outside of our invention, we have not described it in detail. Piston D is 55 worked from a cylinder (not shown) placed above and containing a piston attached to the plunger-rod D' and actuated by steam-pressure. By this means the passages allow the fluid to pass from one side to the other of the 60 plunger, and so cause a reduction in resistance to the said plunger, and thus the speed of the plunger-rod and piston of the steam-cylinder is accelerated, and the momentum thus obtained is applied to positively actuate 65 the valve controlling the supply of steam to the steam-cylinder.

Our invention resides wholly in the grooves by which the fluid can pass from one side of the plunger to the other when the plunger 70 nears the end of its stroke in either direction, thus reducing the resistance usually offered at this point to pump-plunger, and the grooves B or ports C can be applied in suitable form to any type of direct-acting pump driven by 75 expansible fluid under pressure, and we have not, therefore, shown the mechanism for operating the pump.

What we claim as our invention is—

In direct-acting pumps, a pump-barrel having closed ends, a piston therein and annularly-arranged passages in the interior walls of the barrel near each end thereof, whereby when the piston is nearing its stroke in either direction the barrel on each side of the piston 85 is in communication substantially as described.

In witness whereof we have hereunto set our hands in the presence of two witnesses.

J. T. JENNINGS.

T. H. C. HOMERSHAM.
